CARRYING CASE CATCH OR LOCK

Gunnar E. Swanson, New Britain, Conn.

Application June 22, 1946, Serial No. 678,623

19 Claims. (Cl. 70—70)

1

The invention relates to a catch or lock adapted for use on a carrying case or suitcase or trunk or chest or any other similar container. The catch or lock comprises two cooperating units, one adapted to be mounted on the body of the case adjacent the cover, and the other adapted to be mounted on the cover of the case adjacent the body.

The general object of the invention is to provide a self-latching catch which is so constructed that, after the pressing of the releasable elements thereof to effect unlatching, it automatically serves to prevent immediate relatching.

A specific object of the invention is to provide a catch having two bolts which are movable manually to effect unlatching and which are so related to the strike that release of one of the bolts before the other enables the bolt so released to engage the strike and hold the strike in an unlatched position.

A further specific object of the invention is to provide a catch which has cam means associated with the strike and with at least one movable bolt for separating the strike from the bolt unit when the bolt is manually moved and which also has means associated with the said cam means for limiting the return movement of the bolt in the engaging direction so as to hold the said bolt out of its strike engaging position.

A still further object of the invention is to provide a strike movably connected with the unit which carries it and movable in opposition to a spring bias away from the bolt carrying unit, this movable strike permitting the before-described preventing of relatching even though the cover itself is too heavy to be moved by the action of the manually movable elements of the catch.

A further object of the invention is to provide, in association with the other features which have been mentioned, a key operated lock for holding the bolts of the catch in their strike engaging positions.

Other objects of the invention will be apparent from the drawings and from the following specification and claims.

In the drawing I have shown in detail two embodiments of the invention, but it will be understood that various changes may be made from the constructions shown, and that the drawing is not to be construed as defining or limiting the scope of the invention, the claims forming a part of this specification being relied upon for that purpose.

Of the drawing,

Fig. 1 is a combined front and sectional view

of a catch embodying the invention, the sectional portion of the view being taken along the line 1—1 of Fig. 2.

Fig. 2 is a vertical sectional view taken along the line 2—2 of Fig. 1.

Fig. 3 is a vertical sectional view taken along the line 1—1 of Fig. 2 and showing the manually movable bolts in their inner positions.

Fig. 4 is a view similar to Fig. 3 but showing one of the bolts released, and showing the strike and connected parts moved accordingly.

Fig. 5 is a view similar to Fig. 3 but showing the strike moved relatively to the unit which carries it and showing the bolts held out of their normal strike engaging positions.

Fig. 6 is a front view of an alternative catch embodying the invention.

Fig. 7 is a side view of the catch shown in Fig. 6.

Fig. 8 is a vertical sectional view taken along the line 8—8 of Fig. 7.

Fig. 9 is a view similar to Fig. 8 but showing the parts in relative positions corresponding to those shown in Fig. 4.

Fig. 10 is a view similar to Fig. 8 but showing the parts in relative positions corresponding to those shown in Fig. 5.

Fig. 11 is a front view of the tumbler.

Fig. 12 is a side view of the tumbler.

Fig. 13 is a side view of a key which may be used for operating the lock.

Referring to the drawing, particularly Figs. 1 to 5 thereof, there are provided two housings or units 10 and 12 adapted to be mounted respectively on the cover 14 of the case immediately adjacent the body 16 thereof and on the said body of the case immediately adjacent the said cover. Preferably and as shown, the unit 10 is mounted on the cover 14 and the unit 12 is mounted on the body 16, and they will be so described, but it will be understood that the invention is not necessarily so limited.

The cover unit 10 carries a strike 18, a portion of which extends downwardly and is provided with two oppositely disposed hooks 20, 20 which preferably face inwardly.

The body unit 12 carries two oppositely disposed bolts 22, 22 which are oppositely movable rectilinearly. The said bolts are provided respectively with hooks 24, 24 which preferably face outwardly and are adapted to engage the hooks 20, 20 of the strike, as shown in Fig. 1. The bolts 22, 22 are provided with longitudinal slots through which extend bosses 26, 26 which assist in holding the bolts in place and in guiding

them for longitudinal movement. The bolts 22, 22 are biased outwardly toward their strike engaging positions by means of coil springs 28, 28. The bolts can be moved inward manually in opposition to the springs 28, 28 by finger pieces 30, 30 normally projecting from the unit 12 at the ends thereof.

Cam means are provided in association with the bolts and with the strike for moving the strike away from the bolt unit, that is, perpendicularly to the directions of bolt movement, such movement taking place when the bolts are moved inwardly in the disengaging directions. Preferably and as shown, this cam means comprises oppositely inclined cam faces 32, 32 on the respective bolts and corresponding oppositely inclined cam faces 34, 34 on the strike. For reasons to be presently set forth, the cam means preferably also comprises two additional oppositely inclined cam faces 36, 36 on the bolts and may include two additional oppositely inclined cam faces 38, 38 on the strike. Each two cam faces 32 and 36 on the bolts are relatively offset to provide a notch between them, and each two cam faces 34 and 38 on the strike are relatively offset to provide a tooth between them. The teeth between the respective pairs of cam faces on the strike are adapted to enter the notches between the respective pairs of cam faces on the bolts.

Fig. 1 shows the catch with the bolts in their normal strike engaging positions. When unlatching is to be effected, the bolts are moved inwardly by means of the finger pieces 30, 30 to the positions shown in Fig. 3. This causes the cam faces 32, 32 and 36, 36 on the bolts to engage the cam faces 34, 34 and 38, 38 on the strike, thus moving the strike away from the bolt unit, as shown in Fig. 3. Then one of the bolts, as for instance the left hand bolt, is released before the other, and this causes the back of the left hand hook 24 to engage the back of the left hand hook 20 on the strike. As shown in Fig. 4, the back faces of the hooks are inclined, and their engagement serves to cam the strike still further away from the bolt unit. The two hooks 24 and 20, being thus engaged, serve to hold the strike separated and the other bolt at the right can then be released to similarly engage the backs of the hooks 24 and 20 at the right. Thus the strike and the parts connected therewith are held in an elevated unlatched position, and the cover is free to be opened at any time. When downward pressure is applied to the cover and thus to the strike, the inclined faces on the hooks cam the bolts inwardly sufficiently to permit relatching.

In order to facilitate release of one bolt, as for instance the left hand bolt, before the other, the corresponding spring is made somewhat stronger than the other spring. In the example shown, the left hand spring 28 can be regarded as substantially stronger than the right hand spring. Thus, when the finger pieces are released simultaneously the tendency is for the left hand bolt to move more rapidly than the right hand bolt, thus engaging the back of its hook with the back of the corresponding hook on the strike. This avoids any necessity for conscious effort on the part of the user to release one bolt before the other.

If both bolts are permitted to move inwardly substantially simultaneously, the cam faces on the strike will remain in engagement with the cam faces on the bolts, thus causing the before-

mentioned teeth on the strike to enter the before-mentioned notches in the bolts. The engagement of the teeth with the notches limits inward movement of the bolts and holds them out of their normal strike engaging positions as shown in Fig. 5.

While the invention is not necessarily so limited, it may be preferable to so mount the strike 18 that it is bodily movable relatively to the unit 10 which carries it, the strike being movable from and toward the bolt carrying unit 12. As shown, the strike 18 is slideable in a slot in the unit 10 and it is biased for movement toward the unit 12 by means of a bow spring 40. The cover 14 to which the unit 12 is attached may be very heavy, or it may be restrained, as by some heavy object placed thereon, or by means of another catch. If the cover is very heavy, or if it is restrained, it is impossible for the unit 10 to be moved upward as shown in Fig. 3. However, when the strike 18 is movable relatively to the unit 10 the strike itself can be moved upward in opposition to the spring 40 by the cam action of the bolts, even though the cover and the unit 10 remain stationary. After the strike has been so moved upward by means of the cam faces on the bolts, the bolts may be permitted to move outwardly substantially simultaneously, and the action of the spring 40 serves to hold the cam faces on the strike in engagement with the cam faces on the bolts, with the result that the teeth on the strike enter the notches in the bolts, as shown in Fig. 5. Thus the bolts are held out of their normal strike engaging positions and the hooks remain out of engagement with each other. The cover remains unlatched and can be lifted at any time.

The spring 40 has sufficient strength to enable it to overcome the springs 28, 28 through the camming action of the backs of the hooks when the cover is to be closed after having been once opened.

The catch shown in Figs. 6 to 13 is for the most part similar in principle to that shown in Figs. 1 to 5, the major difference being that the bolts are movable pivotally instead of rectilinearly. There are provided two housings or units 42 and 44 adapted to be mounted respectively on the cover 14 of the case and on the body 16 thereof.

The cover unit 42 carries a strike 46 which extends laterally beyond the sides of the unit 42 and which also extends downwardly and is provided with two oppositely disposed hooks 48, 48 which preferably face inwardly.

The body unit 44 carries two oppositely disposed bolts 50, 50 which are mounted for pivotal movement about axes perpendicular to the face of the unit 44. As shown, the bolts 50, 50 are pivoted on bosses 52, 52. The said bolts are provided respectively with hooks 54, 54 which preferably face outwardly and are adapted to engage the hooks 48, 48 of the strike as shown in Fig. 8. Inward movement of the bolts is limited by a stop 56 forming a part of the unit 44, and outward movement is limited by the engagement of the bottom end portions of the bolts with the lower portion of the main body of the unit 44. The bolts 50, 50 are biased outwardly toward their strike engaging positions by means of a single U-shaped spring 58, the lower portion of which is seated in a slot in the unit 44, and the upper diverging legs of which have prongs seated in notches in the bolts. The bolts have outwardly projecting portions 60, 60 which serve as finger pieces which can be manually engaged

to move the bolts inwardly in opposition to the spring 58.

Cam means are provided in association with the bolts and with the strike for moving the strike away from the bolt unit, that is, perpendicular to the general directions of movement of the upper hook portions of the bolts, such movement of the strike taking place when the bolts are moved inwardly in the disengaging directions. Preferably and as shown, this cam means comprises oppositely inclined cam faces 62, 62 on the strike and corresponding oppositely inclined cam faces 64, 64 on the respective bolts. Downwardly projecting teeth are provided at the inner edges of the cam faces 62, 62 and the bolts are preferably provided with two additional oppositely inclined cam faces 66, 66 also adapted to engage the cam faces 62, 62 on the strike. The cam faces 64, 64 and 66, 66 on the bolts are relatively offset to provide a notch between them. The said teeth on the strike are adapted to enter the notches between the respective pairs of cam faces on the bolts.

Preferably there is provided a key operated lock for holding the bolts in their strike engaging positions as shown in Fig. 8. As shown, the lock comprises a tumbler 68 which is vertically movable between lugs 70, 70 projecting forwardly from the rear wall of the unit 44. As shown in Figs. 11 and 12, the tumbler 68 is essentially a flat plate having a forwardly projecting flange 72 at the top and a forwardly projecting flange 74 at the bottom. When the tumbler is in its upper position, as shown in Fig. 8, the flange 72 is positioned between the bolts and prevents inward movement thereof. When the tumbler 68 is in its lower position as shown in Fig. 9, the flange 72 is opposite two notches formed in the inner faces of the bolts, and the bolts are thus free to swing inwardly. The tumbler is operated by means of a key such as 76 which can be inserted through a keyhole 78 in the front wall of the unit 44 and through a recess 80 in the tumbler. The key is shown in section in Fig. 11, the tumbler being in its upper position. It will be seen that when the key is turned in the counter-clockwise direction a portion thereof enters the notch at the left side of the recess 80 thus causing the tumbler to move from its upper position to its lower position. When the key is turned in the clockwise direction the tumbler is moved from its lower position to its upper position. The tumbler is releasably held in either its upper position or its lower position by means of a projection 82 formed integrally on the right leg of the spring 58. This projection 82 engages the right end of the flange 74 on the tumbler and thus holds the tumbler in either its upper position or its lower position.

Fig. 8 shows the catch with the bolts in their normal strike engaging positions. When unlatching is to be effected the bolts are unlocked by means of the key as already described and then they are moved inwardly by means of the portions 68, 68 thereon to their disengaged positions. The left hand bolt is shown in Fig. 9 as being in such disengaged position. When both bolts are moved to their inward disengaged positions the cam faces 64 and 66 thereon engage the cam faces 62, 62 on the strike to move the strike upward from the position shown in Fig. 8 to the position shown in Fig. 9. Then one of the bolts, as for instance the right hand bolt, is released before the other bolt and this causes the back of the right hand hook 54 to engage the back of

the right hand hook 48 on the strike. As shown in Fig. 9, the back faces of the hooks are inclined and their engagement serves to cam the strike still further away from the bolt unit. The two hooks 54 and 48, being thus engaged, serve to hold the strike separated and the other bolt at the left can then be released to similarly engage the backs of the hooks 54 and 48 at the left. Thus the strike and the parts connected therewith are held in an elevated unlatched position and the cover is free to be opened at any time. When downward pressure is applied to the cover and thus to the strike, the inclined surfaces on the hooks cam the bolts inwardly sufficiently to permit relatching.

In order to facilitate release of one bolt, as for instance the right hand bolt, before the other, the bolt to be so released is given a stronger spring bias. As illustrated, both bolts are biased by the same spring 58 but the right hand leg of this spring abuts against the flange 74 on the tumbler and thus has a shorter flexing radius. The result is that the spring 58 applies a much heavier pressure against the right hand bolt than it does against the left hand bolt. When the two bolts are released simultaneously, the tendency is for the right hand bolt to move more rapidly than the left hand bolt, thus engaging the back of its hook with the back of the corresponding hook on the strike. This avoids any necessity for conscious effort on the part of the user to release one bolt before the other.

If both bolts are permitted to move inward substantially simultaneously, the cam faces on the strike will ordinarily remain in engagement with the cam faces on the bolts thus causing the before-mentioned teeth on the strike to enter the before-mentioned notches in the bolts. The engagement of the teeth with the notches limits inward movement of the bolts and thus holds them out of their normal strike engaging positions as shown in Fig. 10. It will be obvious that with the parts in the position shown in Fig. 10 the cover is free to be lifted at any time.

For the reasons fully explained in connection with the catch shown in Figs. 1 to 5, it may be preferable to mount the strike 46 so that it is bodily movable relatively to the unit 42 from and toward the bolt carrying unit 44. As shown, the strike is provided with a slot through which projects a portion of the unit 42 and the strike is vertically slidably with respect to the unit. The strike is biased for movement toward the bolt carrying unit 44 by means of a spring 84. When the cover 14 carrying the unit 42 is heavy or is restrained, the strike 46 can be moved upward relatively to the said unit 42 and in opposition to the spring 84 by the cam action of the bolts, such upward movement of the strike taking place even though the cover and the unit remain stationary. After the strike has been so moved upward by means of the cam faces on the bolts, the bolts may be permitted to move outwardly substantially simultaneously and the action of the spring 84 serves to hold the cam faces on the strike in engagement with the cam faces on the bolts with the result that the teeth on the strike enter the notches on the bolt as shown in Fig. 10. Thus the bolts are held out of their normal strike engaging positions and the hooks remain out of engagement with each other. The cover remains unlatched and can be lifted at any time.

The spring 84 has sufficient strength to enable it to overcome the spring 58 through the camming action of the backs of the hooks when the

cover is to be closed after having been once opened.

What I claim is:

1. A catch for use on a carrying case or the like comprising in combination, two units mountable respectively on the case and on the case cover, a strike on one unit having a hook and a cam face, two separately movable bolts on the other unit, a hook on one bolt engageable with the strike hook, a cam face on the other bolt engageable with the cam face on the strike, spring means for biasing the bolts in the directions to engage the bolt hook with the strike hook and to disengage the bolt cam face from the strike cam face, and manually engageable means for simultaneously moving the bolts in opposition to the spring means to disengage the bolt hook from the strike hook and to engage the bolt cam face with the strike cam face, the said cam face on one bolt when engaged with the strike cam face serving to move the strike away from the bolt unit to a position such that upon release of the other bolt the hook thereon will engage the back of the strike hook to hold the strike in its last said position.

2. A catch for use on a carrying case or the like comprising in combination, two units mountable respectively on the case and on the case cover, a strike on one unit having two oppositely disposed hooks, two oppositely disposed and oppositely movable hook bolts on the other unit which are spring biased to engage the respective strike hooks and which are manually movable out of their engaging positions, and cam means on the strike and on at least one bolt serving upon disengaging movement of the cam carrying bolt to move the strike relatively to the bolt unit sufficiently to permit the back of the hook of the other bolt upon release thereof before the cam carrying bolt to engage the back of the corresponding strike hook and thus hold the strike out of its normal bolt engaging position.

3. A catch for use on a carrying case or the like comprising in combination, two units mountable respectively on the case and on the case cover, a strike on one unit having two oppositely disposed hooks, two oppositely disposed and oppositely movable hook bolts on the other unit which are spring biased to engage the respective strike hooks and which are manually movable out of their engaging positions, and cam means serving upon simultaneous disengaging movement of both bolts to move the strike relatively to the bolt unit sufficiently to permit the back of the hook of one bolt upon release thereof before the other to engage the back of the corresponding strike hook and thus hold the strike out of its normal bolt engaging position.

4. A catch for use on a carrying case or the like comprising in combination, two units mountable respectively on the case and on the case cover, a strike on one unit having two oppositely disposed hooks, two oppositely inclined cam faces on the strike, two oppositely disposed and oppositely movable hook bolts on the other unit which are spring biased to engage the respective strike hooks and which are manually movable out of their engaging positions, and two oppositely inclined cam faces on the respective bolts engageable with the respective cam faces on the strike and serving upon simultaneous disengaging movement of both bolts to move the strike relatively to the bolt unit sufficiently to permit the back of the hook of one bolt upon release thereof before the other to engage the back of the corre-

sponding strike hook and thus hold the strike out of its normal bolt engaging position.

5. A catch for use on a carrying case or the like comprising in combination, two units mountable respectively on the case and on the case cover, a strike on one unit having two oppositely disposed hooks, two oppositely disposed and oppositely movable hook bolts on the other unit which are engageable with the respective strike hooks and which are manually movable out of their engaging positions, cam means serving upon simultaneous disengaging movement of both bolts to move the strike away from its bolt engaging position, and two springs for biasing the respective bolts toward their strike engaging positions, one spring being stronger than the other so that upon release of manual pressure on the bolts one of them will move before the other to cause the back of the hook thereof to engage the back of the corresponding strike hook and thus hold the strike out of its normal bolt engaging position.

6. A catch for use on a carrying case or the like comprising in combination, two units mountable respectively on the case and on the case cover, a strike on one unit having a hook, a movable hook bolt on the other unit which is spring biased to engage the strike hook and which is manually movable out of its engaging position, cam means serving upon disengaging movement of the bolt to relatively move the strike away from the bolt unit, and means dependent on continued engagement of the cam means during movement of the bolt in its engaging direction for limiting such movement so as to hold the bolt out of its normal strike engaging position.

7. A catch for use on a carrying case or the like comprising in combination, two units mountable respectively on the case and on the case cover, a strike on one unit having two oppositely disposed hooks, two oppositely disposed and oppositely movable hook bolts on the other unit which are spring biased to engage the respective strike hooks and which are manually movable out of their engaging positions, cam means serving upon simultaneous disengaging movement of both bolts to relatively move the strike away from the bolt unit, and means dependent on continued engagement of the cam means during movement of the bolts in their engaging directions for limiting such movement so as to hold the bolts out of their normal strike engaging positions.

8. A catch for use on a carrying case or the like comprising in combination, two units mountable respectively on the case and on the case cover, a strike on one unit having two oppositely disposed hooks, two oppositely inclined cam faces on the strike with teeth at opposite ends thereof, two oppositely disposed and oppositely movable hook bolts on the other unit which are spring biased to engage the respective strike hooks and which are manually movable out of their engaging positions, and two pairs of oppositely inclined cam faces on the respective bolts which are offset to form notches between them and which are engageable with the respective cam faces on the strike to move the strike relatively to the bolt unit upon simultaneous disengaging movement of both bolts, the notches between the cam faces on the bolts being engageable by the teeth on the strike upon the movement of both bolts in their engaging directions so as to limit such movement and hold the bolts out of their normal strike engaging positions.

9. A catch for use on a carrying case or the like comprising in combination, two units mountable

respectively on the case and on the case cover, a strike on one unit having two oppositely disposed hooks, two oppositely disposed and oppositely movable hook bolts on the other unit which are spring biased to engage the respective strike hooks and which are manually movable out of their engaging positions, cam means serving to move the strike relatively to the bolt unit upon simultaneous disengaging movement of both bolts, the back of one hook of the strike after such movement thereof being engageable by the back of the hook of one bolt upon the release thereof before the other bolt so as to hold the strike out of its normal bolt engaging position, and means dependent on continued engagement of the cam means during movement of both bolts in their engaging directions for limiting such movement so as to hold the bolts out of their normal strike engaging positions.

10. A catch for use on a carrying case or the like comprising in combination, two units mountable respectively on the case and on the case cover, a strike on one unit having two oppositely disposed hooks, two oppositely inclined cam faces on the strike with teeth at opposite ends thereof, two oppositely disposed and oppositely movable hook bolts on the other unit which are spring biased to engage the respective strike hooks and which are manually movable out of their engaging positions, and two pairs of oppositely inclined cam faces on the respective bolts which are offset to form notches between them and which are engageable with the respective cam faces on the strike to move the strike relatively to the bolt unit upon simultaneous disengaging movement of both bolts, the back of one hook of the strike after such movement thereof being engageable by the back of the hook of one bolt upon the release thereof before the other bolt so as to hold the strike out of its normal bolt engaging position and the notches between the cam faces on the bolts being engageable by the teeth on the strike upon the simultaneous movement of both bolts in their engaging directions so as to limit such movement and hold the bolts out of their normal strike engaging positions.

11. A catch for use on a carrying case or the like comprising in combination, two units mountable respectively on the case and on the case cover, a strike on one unit having a hook, the strike being bodily movable relatively to its unit from and toward the other unit, a spring for biasing the strike for relative movement toward the said other unit, a movable hook bolt on the other unit which is spring biased to engage the strike hook and which is manually movable out of its engaging position, cam means serving upon disengaging movement of the bolt to move the strike relatively to the bolt unit and also relatively to its own unit when the last said unit is held stationary, the strike biasing spring serving to hold the cam means in engagement during movement of the bolt in its engaging direction, and means dependent on the said continued engagement of the cam means during the said disengaging movement and serving to limit such movement of the bolt and hold it out of its normal strike engaging position.

12. A catch for use on a carrying case or the like comprising in combination, two units mountable respectively on the case and on the case cover, a strike on one unit having two oppositely disposed hooks, the strike being bodily movable relatively to its unit from and toward the other unit, a spring for biasing the strike for relative

movement toward the said other unit, two oppositely disposed and oppositely movable hook bolts on the other unit which are spring biased to engage the respective strike hooks and which are manually movable out of their engaging positions, cam means serving upon simultaneous disengaging movement of both bolts to move the strike relatively to the bolt unit and also relatively to its own unit when the last said unit is held stationary, the strike biasing spring serving to hold the cam means in engagement during movement of the bolts in their engaging directions, and means dependent on the said continued engagement of the cam means during the said engaging movement and serving to limit such movement of the bolts and hold them out of their normal strike engaging positions.

13. A catch for use on a carrying case or the like comprising in combination, two units mountable respectively on the case and on the case cover, a strike on one unit having two oppositely disposed hooks, the strike being bodily movable relatively to its unit from and toward the other unit, a spring for biasing the strike for relative movement toward the said other unit, two oppositely inclined cam faces on the strike with teeth at opposite ends thereof, two oppositely disposed and oppositely movable hook bolts on the other unit which are spring biased to engage the respective strike hooks and which are manually movable out of their engaging positions, and two pairs of oppositely inclined cam faces on the respective bolts which are offset to form notches between them and which upon simultaneous disengaging movement of both bolts are engageable with the respective cam faces on the strike to move the strike relatively to the bolt unit and also relatively to its own unit when the last said unit is held stationary, the strike biasing spring serving to hold the strike cam faces in engagement with the bolt cam faces upon movement of the bolts in their engaging directions and the notches between the cam faces on the bolts being thereupon engageable by the teeth on the strike so as to limit such movement of the bolts and hold them out of their normal strike engaging positions.

14. A catch for use on a carrying case or the like comprising in combination, two units mountable respectively on the case and on the case cover, a strike on one unit having two oppositely disposed hooks, the strike being bodily movable relatively to its unit from and toward the other unit, a spring for biasing the strike for relative movement toward the said other unit, two oppositely disposed and oppositely movable hook bolts on the other unit which are spring biased to engage the respective strike hooks and which are manually movable out of their engaging positions, cam means serving upon simultaneous disengaging movement of both bolts to move the strike relatively to the bolt unit and also relatively to its own unit when the last said unit is held stationary, the back of one hook of the strike after such movement thereof being engageable by the back of the hook of one bolt upon the release thereof before the other bolt so as to tend to hold the strike out of its normal bolt engaging position, and means serving during the engaging movement of the bolts to limit such movement and hold them out of their normal strike engaging positions, the said means being dependent on the continued engagement of the cam means during such engaging movement resulting from the action of the strike biasing spring.

15. A catch for use on a carrying case or the like comprising in combination, two units mountable respectively on the case and on the case cover, a strike on one unit having two oppositely disposed hooks, two oppositely disposed hook bolts on the other unit oppositely movable rectilinearly, the said bolts being spring biased to engage the respective strike hooks and being manually movable out of their engaging positions, and cam means serving upon simultaneous disengaging movement of both bolts to move the strike transversely of the directions of rectilinear movement sufficiently to permit the back of the hook of one bolt upon release thereof before the other to engage the back of the corresponding strike hook and thus hold the strike out of its normal bolt engaging position.

16. A catch for use on a carrying case or the like comprising in combination, two units mountable respectively on the case and on the case cover, a strike on one unit having two oppositely disposed hooks, two oppositely inclined cam faces on the strike with teeth at opposite ends thereof, two oppositely disposed hook bolts on the other unit oppositely movable rectilinearly, the said bolts being spring biased to engage the respective strike hooks and being manually movable out of their engaging positions, and two pairs of oppositely inclined cam faces on the respective bolts which are offset to form notches between them and which are engageable with the respective cam faces on the strike to move the strike transversely of the directions of rectilinear movement upon simultaneously disengaging movement of both bolts, the notches between the cam faces on the bolt being engageable by the teeth on the strike upon the movement of both bolts in their disengaging directions so as to limit such movement and hold the bolts out of their normal strike engaging positions.

17. A catch for use on a carrying case or the like comprising in combination, two units mountable respectively on the case and on the case cover, a strike on one unit having two oppositely disposed hooks, two oppositely disposed hook bolts on the other unit pivotally movable in opposite directions about axes perpendicular to the face of the housing, the said bolts being engageable with the respective strike hooks and being manually movable out of their engaging positions, cam means serving upon simultaneous disengaging movement of both bolts to move the strike away from its bolt engaging position, and two springs for biasing the respective bolts for pivotal movement toward their strike engaging positions, one spring being stronger than the other so that upon release of manual pressure on the bolts one of them will move pivotally before the other to cause the back of the hook thereof to engage the back of the corresponding strike hook and thus hold the strike out of its normal bolt engaging position.

18. A catch for use on a carrying case or the like comprising in combination, two units mount-

able respectively on the case and on the case cover, a strike on one unit having two oppositely disposed hooks, two oppositely disposed hook bolts on the other unit pivotally movable in opposite directions about axes perpendicular to the face of the housing, the said bolts being spring biased to engage the respective strike hooks and being manually movable out of their engaging positions, cam means serving upon simultaneous pivotal disengaging movement of both bolts to relatively move the strike away from the bolt unit, and means dependent on continued engagement of the cam means during pivotal movement of the bolts in their engaging directions for limiting such movement so as to hold the bolts out of their normal strike engaging positions.

19. A catch for use on a carrying case or the like comprising in combination, two units mountable respectively on the case and on the case cover, a strike on one unit having two oppositely disposed hooks, the strike being bodily movable relatively to its unit from and toward the other unit, a spring for biasing the strike for relative movement toward the said other unit, two oppositely inclined cam faces on the strike with teeth at opposite ends thereof, two oppositely disposed hook bolts on the other unit pivotally movable in opposite directions about axes perpendicular to the face of the housing, the said bolts being spring biased to engage the respective strike hooks and being manually movable out of their engaging positions, and two pairs of oppositely inclined cam faces on the respective bolts which are offset to form notches between them and which upon simultaneous pivotal disengaging movement of both bolts are engageable with the respective cam faces on the strike to move the strike relatively to the bolt unit and also relatively to its own unit when the last said unit is held stationary, the strike biasing spring serving to hold the strike cam faces in engagement with the bolt cam faces upon pivotal movement of the bolts in their engaging directions and the notches between the cam faces on the bolts being thereupon engageable by the teeth on the strike so as to limit such movement of the bolts and hold them out of their normal strike engaging positions.

Certificate of Correction

Patent No. 2,478,434

August 9, 1949

GUNNAR E. SWANSON

It is hereby certified that errors appear in the printed specification of the above numbered patent requiring correction as follows:

Column 5, line 43, for "recess 89" read *recess 80*; line 50, for "Whe" read *When*; column 6, line 12, for "appliied" read *applied*; column 12, line 47, for "ono" read *on*; and that the said Letters Patent should be read with these corrections therein that the same may conform to the record of the case in the Patent Office.

Signed and sealed this 3rd day of January, A. D. 1950.

[**SEAL**]

THOMAS F. MURPHY,
Assistant Commissioner of Patents.
